WILLIAM WEILER, OF WASHINGTON, NEW JERSEY.

Letters Patent No. 76,279, dated March 31, 1868.

IMPROVED PORTABLE ROCK-DRILLING MACHINE.

The Schedule referred to in these Letters Patent and making part of the same.

TO ALL WHOM IT MAY CONCERN:

Be it known that I, WILLIAM WEILER, of Washington, Warren county, New Jersey, have invented a Portable Rock-Drilling Machine for quarries, &c.; and I do hereby declare the following to be a full, clear, and exact description of the same.

My invention consists of a portable rock-drilling machine, fully described hereafter, to be operated either by hand or power, for the purpose of drilling holes of moderate depth, such as are generally drilled by hand in stone-quarries, for blasting, &c.

In order to enable others skilled in the art to make and use my invention, I will now proceed to describe its construction and operation, reference being had to the accompanying drawing, which forms a part of this specification, and in which—

Figure 1 is a front elevation of my portable rock-drilling machine for quarries, &c.

Figure 2, a sectional elevation of the same.

Figure 3, a sectional plan view on the line 1 2, fig. 2.

Figure 4, a sectional plan on the line 3 4, fig. 2; and

Figure 5, a detached view.

Similar letters refer to similar parts throughout the several views.

The frame consists of four horizontal bars, A, connected together, as shown in fig. 3, so as to form a base, and of four uprights, B, B¹, B², and B³, secured to the base, and connected together at the top by cross-pieces a. The driving-shaft C turns in suitable bearings in the opposite uprights, B and B¹, and has at one end a pulley, b, provided with a crank, b', and at the opposite end a pinion, c, gearing into a cog-wheel, c', of a shaft, D, which also turns in the opposite uprights. Upon this latter shaft are two pulleys, E and E', connected by endless bands d and d' to pulleys F and F', hung to a shaft, G, which turns in suitable bearings at the upper ends of the uprights B and B¹. The endless bands d and d' are connected together by two plates, e, which are riveted or otherwise secured to them at equal distances from each other, and to the band, d, are secured two projections, provided with anti-friction rollers f; a dog, g, being also secured to the band, d', at a point nearly opposite to each of the rollers f, for a purpose described hereafter. A weight, H, is arranged to slide in vertical guides, h, secured to the uprights B² and B³, and is operated, as will be hereafter described, by a spring-catch or hook, I, which is hung to it by a pin, h', and projects between the endless bands d and d' in the path of the plates e. Two plates, K and K', are connected together, and are secured in any desired position on the guides h, above the weight, by a screw-rod and tightening-nut, j, and a pin, j', extends across the recessed portion of the plate K, as shown in figs. 2 and 3, for a purpose described hereafter. The drill-rod L, between the uprights B² and B³, slides in, and is guided by plates k and l, both of which, as shown in figs. 2 and 5, can be readily detached from the frame; and to the drill-rod between these guiding-plates is secured a ratchet-wheel, m, which can be adjusted to any position on the rod by means of a set-screw, m'. The drill-rod L may be raised by a bell-crank lever, P, which is hung to a projection, n, of the frame of the machine, the forked arm of the lever passing around the drill-rod, beneath its ratchet-wheel m, as shown in fig. 2, and these forked ends which bear against the under side of the ratchet-wheel may be provided with anti-friction rollers, so as not to interfere with the motion of the wheel. The opposite bent arm of the lever passes beneath and is operated by the anti-friction rollers f of the endless band, d, as will be hereafter described. A rod, p, having a lug, p', slides in a projection, q, of the upright, B¹, and is hung to the outer end of an arm, r, which is pivoted to a projection of the upright, B³, and a spiral spring, s, upon the rod p, has a tendency to turn the arm r in the direction of the arrow 1, fig. 4. Two crossed levers, t and t', are hung to the arm r, in such a position that two of their arms shall embrace and serve as pawls for the ratchet-wheel m of the drill-rod, the opposite arms of the said levers being connected by a spiral spring, u, which causes the ends of the pawls to engage with the teeth of the ratchet-wheel.

Operation.

The machine is placed in the desired position, upon the rock to be drilled, and is operated either by hand by means of the crank b', or by a belt passing round the pulley b from an adjoining portable engine, the driving-shaft and the pulleys E and F turning in the direction of their arrows, fig. 2. The bands d and d' travel together, and at the same speed, in the direction of their arrows, until one of the plates e strikes the spring-hook I of the

weight H. The latter is then raised until the bevelled end of the spring-hook strikes the pin j' of the plate K, which withdraws the hook from the plate e, and thus releases the weight, which falls and strikes the upper end of the drill-rod. The endless bands still continue to turn, and the second plate e catches and raises the hook I and its weight, but before the latter is released, one of the anti-friction rollers f of the band d, strikes and turns the bell-crank lever P, and thus raises the lower end of the drill clear of the rock. Then, before the drill is lowered, one of the dogs g of the band d' strikes the lug p' of the rod p, and moves the latter and the arm r in the direction of the arrow 2, fig. 4. The ratchet-wheel m and drill-rod are thus partially turned by the pawl, t, and as soon as the lug p' is released, the second pawl, t, will, by the action of the spring s of the rod p, be drawn back, and still farther turn the ratchet-wheel and drill-rod. The roller f then releases the lever P, and the drill-rod falls until it again rests upon the rock, after which the spring-hook I is released by the pin j' , and the weight falls upon the drill, thus causing the latter to make a second cut. The weight is elevated a third time, and the drill raised slightly, and again turned before the weight descends upon it, and this operation is repeated until the drill has descended sufficiently into the rock to render it necessary to raise the ratchet-wheel, m, which can be readily done after loosening the set-screw, m'.

When a hole of moderate depth has been drilled, it becomes necessary to remove the detritus which interferes with the proper working of the drill; to do which, the latter must first be withdrawn, and its guiding-plates k and l detached from the frame of the machine. After removing the powdered rock, the drill is again inserted into the hole, and is by means of its plates k and l properly secured to the frame of the machine, after which the operation is continued until a hole of the desired depth has been drilled.

The above machine performs its work quickly, and can readily be removed from place to place, its bars A being sufficiently extended to give it a firm foundation, and it is especially adapted for use in stone-quarries.

Instead of the extended base, A, the machine may be caused to rest upon adjustable legs, hinged to the upper portion of the frame; the advantage gained by the latter plan being that the machine can always be maintained in a vertical position upon an unequal foundation, or it may be slightly inclined, when necessary, so as to drill an inclined hole.

I claim as my invention, and desire to secure by Letters Patent—

1. The drill-rod L, operated by a sliding weight, H, and raised and partially turned between each of the blows of the weight by the anti-friction-rollers f and dogs g of the endless bands d and d', through the medium of the levers and devices, herein described, or their equivalents, all substantially as and for the purpose specified.
2. The drill-rod L, secured to the frame of the machine by plates k and l in such a manner as to be readily detached from the same, as described.
3. The sliding weight H, and its spring-catch I, elevated by the plates e of the endless bands d and d', and released by the pin j' of the adjustable plate K, in the manner and for the purpose specified.

In testimony whereof, I have signed my name to this specification in the presence of two subscribing witnesses.

WM. WEILER.
